V. N. HANSEN,
CRANK CASE OILER.
APPLICATION FILED FEB. 24, 1919.

1,323,631.

Patented Dec. 2, 1919.

UNITED STATES PATENT OFFICE.

VIGGO N. HANSEN, OF WINNETKA, ILLINOIS, ASSIGNOR TO STANDEX MANUFACTURING CORPORATION, OF CHICAGO, ILLINOIS, A CORPORATION OF DELAWARE.

CRANK-CASE OILER.

1,823,631.

Specification of Letters Patent.

Patented Dec. 2, 1919.

Application filed February 24, 1919. Serial No. 278,809.

To all whom it may concern:

Be it known that I, VIGGO N. HANSEN, a citizen of the United States, residing at Winnetka, in the county of Cook and State 5 of Illinois, have invented certain new and useful Improvements in Crank-Case Oilers, of which the following is a specification, reference being had to the accompanying drawings, forming a part thereof.

10 The purpose of this invention is to provide an improved device for supplying oil to an engine crank case and governing the level thereof, particularly adapted to meet the exigencies arising by change of inclination of the vehicle on which the engine whose crank case is to be supplied is mounted. It consists in the elements and features of construction shown and described as indicated in the claims.

20 In the drawings:

Figure 1 is a vertical section in fore-and-aft direction through a portion of a crank case of an engine equipped with this invention, the particular parts constituting the 25 invention being fully shown in section in said plane.

Fig. 2 is a bottom plan view of the oil-governing receptacle.

Fig. 3 is an end view of the inlet fitting 30 and valve therein.

In the drawing, 1 represents any source of the lubricating oil to be supplied to the crank case of an engine, as a tank which may be located at a suitably high position under 35 the seat of the automobile. 2 is a pipe through which the oil is supplied from the tank, 1, to a governing device consisting of a receptacle, 3, of which the inlet from the tank, 1, is afforded through a fitting, 4, 40 whose discharge port is controlled by a ball valve, 5, the valve being controlled at its seating and unseating by a float, 6, in the receptacle, 3. The receptacle is formed by means of a top plate, 3^a, and a bottom plate 45 3^b, and a body member, 3^c, preferably of glass so that the condition of supply in the receptacle can at all times be readily observed, the top and bottom plate being clamped on the glass body by means of four 50 vertical posts, 8, 8, 8, 8, suitable packing, 7, being interposed between the ends of the glass body and the top and bottom plates respectively. The receptacle is connected with the crank case by means of a pipe, 10, 55 which extends rearwardly from the crank

case under the bottom plate of the receptacle to a fitting, 11, near the side of said bottom and the side of the receptacle remote from the crank case, so that an outlet tube, 12, secured to said fitting inside the receptacle stands up in the receptacle at the side thereof remote from the crank case and beyond the float. The intake mouth of said tube, 12, is positioned at a level somewhat below that at which the float seats the inlet 60 valve which is hereinafter referred to as the high liquid level of the governing receptacle. The pipe, 10, serves to assist in supporting the receptacle, 3, and positioning it definitely and safely against displacement 65 from the jarring to which it is subjected in the travel of the vehicle, by being clamped to the bottom plate by means of a clamp, 15, which is applied under the pipe and secured by the nuts on the ends of two of the 70 bolts, 8, 8, by which the top and bottom plates are clamped onto the glass body as above described. The fitting, 11, beside the opening, 11^a, at which the pipe, 10, is connected, and the opening leading upward at 75 which the outlet tube, 12, is connected, has a downward opening at which a drain cock, 17, is connected, said drain cock serving to drain the crank case without draining the receptacle more than to the level of the intake mouth of the outlet tube, 12.

In previous devices of this character and for a like purpose, the pipe connections from the level-governing receptacle to the crank case have been connected for outlet of the 90 receptacle at substantially the bottom thereof; with the result that, when the vehicle is on a down-hill grade, the governing device, being necessarily at the rear end of the engine, is lifted relatively to the crank case so 95 that the contents of the receptacle will drain out into the crank case, and the inlet valve being thereby opened by the lowering of the float, there is constant flow of oil from the main elevated tank through the governing 100 device into the crank case, with the result of flooding the latter or filling it to a higher level than is desirable. Such flooding of the crank case is prevented in the structure shown by locating the outlet from the receptacle, 3,—which is the intake mouth of the tube, 12, at its upper end,—at the side of the receptacle remote from the crank case, at a point below the high liquid level of the 105 governing receptacle and substantially at 110

the level predetermined as the highest permissible level for the liquid in the crank case when the engine is inclined downward away from the governing receptacle, *i. e.*, when the vehicle is on a descending grade. This may be understood upon considering the condition created by the inclination of the receptacle resulting from the vehicle being on a descending grade, which is, that 5 the valve-seating level of the liquid in the receptacle shifts from that indicated at $x-x$ to that indicated by dotted line, $y-y$, while the level in the crank case at an assumed vertical mid-plane, Z , thereof, rises a small 10 distance $z-z$; and that at the limit of this rise in the crank case the intake mouth of the tube, 12, is above the level of the liquid in the governing receptacle; and the valve, 5, being held closed at this level, no liquid comes into 15 or goes out of the receptacle while the vehicle remains in that inclined position or becomes more inclined. It will be seen that the height of the intake mouth, 12, may be such that it would be uncovered by a slight 20 change of inclination of the vehicle; but since a limited rise of level of the oil in the crank case is permissible, the height of the intake of the tube, 12, is desirable, such as to allow the oil to continuously flow to the 25 crank case while the vehicle is inclined to a less extent than would cause the oil to rise beyond that permissible height in the crank case, rather than to have the oil flow cut off for so large a part of the time as would result 30 from making the tube, 12, so low that very slight inclination of the vehicle would thus cut it off. While it will be obvious, as above stated that so long as the vehicle remains on the down-grade at an inclination 35 great enough to leave the intake mouth of the pipe, 10, above the valve closing level of the liquid in the governing receptacle, the crank case will receive no additional supply of lubricating oil, this is not objectionable, 40 because the supply normally maintained in the crank case while the vehicle is horizontal or approximately so, is sufficient without further replenishing for many miles of travel, and restoration of the vehicle to approximately horizontal position for even a 45 few seconds will serve to fully replenish the supply.

Also in former devices the governing receptacle has been provided with an air vent, supposed to be necessary in order to permit the liquid to drain from it freely by gravity into the crank case, with the result that when the vehicle is on the up grade, the oil is liable to flow from the crank case back 50 into the receptacle and out through the air vent, thereby not only depriving the crank case of lubricating oil which must be subsequently re-supplied, but also causing waste and creating liability to fires by reason of the overflow of the oil onto the en-

gine parts. In the construction shown the receptacle, 3, has no atmosphere inlet at the top, none being necessary since the main supply receptacle, 1, is necessarily always provided with an atmosphere inlet so that the liquid may flow from it by gravity, and any supply accumulating in the receptacle, 3, above the intake of the outlet tube, 12, causes the compression of the air imprisoned in the receptacle above the liquid therein, which insures discharge of the liquid from the receptacle into the crank case under all conditions without a direct atmosphere inlet for that purpose; and in any event, even if there were no compression of the imprisoned air (which will be only slight because the air will tend to pass up in bubbles through the liquid flowing down through the pipe, 2), the head of liquid in the main supply tank, 1, will always be operative to force the flow of liquid from the receptacle into the crank case when the valve, 5, is opened for liquid flow into the receptacle, and any lowering of the liquid level in the crank case below the level to which it will be raised while the receptacle is filling to the level at which the float will close the inlet valve, will cause the head of the liquid to open the inlet valve to admit a further supply and discharge a corresponding supply into the crank case.

The valve, 5, is checked against movement beyond a very short distance from its seat, by the detent, 4°, and sucked inward from the margin of the skirt, 4^a, of the fitting, 4, as seen in Figs. 1 and 3. The purpose and advantage of this is that thereby the flow of lubricating oil from the elevated tank, 1, is limited to slow dropping, the rate being easily made as low as ten drops per minute; and this low rate, while permitting an entirely adequate supply to meet the consumption in the engine crank case, prevents any danger of flooding the crank case under any ordinary circumstances of travel, even if the float by becoming water-logged should fail to operate for closing the valve.

I claim:

1. In a device for the purpose indicated in combination with a chamber in which the liquid level is to be governed, a receptacle having at its upper part an inlet fitting and a float-operated valve controlling the inlet; an outlet comprising a duct having its intake in the receptacle positioned below the valve-seating level of the liquid and at a substantial distance above the bottom of the receptacle, and substantially at the predetermined highest level of liquid to be permitted in the liquid-level-governed chamber when the latter is lowered with respect to the liquid-level-governing receptacle; and a conduit from said duct to the liquid-level-governed chamber.

2. In the construction defined in claim 1,

the outlet duct intake being at the side of the liquid-level-governing chamber remote from the liquid-level-governed chamber.

3. In the construction defined in claim 1, 5 the conduit consisting of a pipe extended from its connection with the outlet duct across under the liquid-level-governing receptacle, and means for clamping said receptacle to said pipe.
- 10 4. In a device for the purpose indicated, in combination with a liquid-level-governed chamber, a main supply tank at a high level for supplying liquid by gravity flow; a liquid-level-governing receptacle at a lower 15 level; a float-operated valve for controlling the gravity discharge from the elevated tank to the liquid-level-governing receptacle; a conduit from said receptacle to the liquid-level-governed chamber, said conduit 20 having its intake from the receptacle located below the high liquid level of the level-governing receptacle, said receptacle being closed except as to its liquid inlet from the elevated tank, and its liquid dis- 25 charge from the level-governed chamber.

5. In a device for the purpose indicated, in combination with a main oil supply tank at a high level; a level-governing receptacle at a lower level; a conduit by which the level-governing receptacle is supplied by 30 gravity from the elevated tank; a valve which controls the discharge of liquid into the level-governing receptacle; a float in said receptacle which controls said valve according to the level of liquid in said 35 receptacle; a level-governed chamber; a conduit from the level-governing receptacle to the level-governed chamber, said conduit having its intake in the level-governing receptacle, at a distance from 40 the bottom thereof, and substantially at the highest liquid level to be permitted in the level-governed chamber when said chamber is lowered relatively to the level-governing chamber. 41

In testimony whereof, I have hereunto set my hand at Chicago, Illinois, this 20th day of February, 1919.

VIGGO N. HANSEN
